VARIABLE RESISTANCE

Floyd E. Riling, Anderson, Ind., assignor to P. R.
Mallory & Co., Inc., Indianapolis, Ind., a cor-
poration of Delaware

Application February 2, 1944, Serial No. 520,726

5 Claims. (Cl. 201—56)

The present invention relates to variable resistances, and, more particularly, to variable resistances, such as rheostats and potentiometers, employed for volume control in radio receivers.

As those skilled in the art know, variable resistances in their most common form comprise a resistance element provided in the form of windings of high resistance wire on an insulative strip or of a suitable substance of high specific resistance deposited upon a suitable base, arranged in a substantially circular shape. Upon this resistance element may slide a movable contact or slider adapted to make electrical connection to any desired point of the element.

Heretofore, considerable difficulty was experienced in providing electrical connection of constant and negligible resistance to the sliding element. It was customary to provide a double slider element one sliding surface of which was resiliently applied to the resistance element, the other sliding surface being applied to a fixed flat contact ring, or its equivalent. This type of structure, however, although employed on a substantial scale, was far from being satisfactory, as two sliding contacts were introduced into the circuit and their resistance was appreciable and also subject to variations due to oxidation of the cooperating contact surfaces. The result was that noise was produced particularly when the control was already in use for some time and such circuit noise necessitated frequent replacement of the otherwise but slightly used control. Some relief was made possible by providing a coil spring wire for electrical connection of the rotative slider and the stationary soldering lug therefor. This type of structure, however, has introduced other complications. As it is considered desirable to insulate the main shaft of the variable resistance from the slider, provision had to be made for positive insulation of the shaft from the coil spring and this could be obtained only by surrounding the corresponding portions of the shaft with a member or sleeve of insulating material. Also the individual turns of the coil spring would frictionally engage the surface of the insulative sleeve provided between the same and the shaft and become entangled with each other. The result was either early destruction of the cylindrical coil spring or increased binding and tension thereof which tended to return the slider toward its normal position of rest so that the slider did not positively maintain its adjustment. Although various suggestions and proposals were made to eliminate this difficulty, none of these suggestions and proposals was completely satis-

factory and successful when carried into practice on a practical and commercial scale.

It is an object of the present invention to eliminate the foregoing difficulties experienced in the construction and operation of conventional variable resistances.

It is another object of the present invention to provide a variable resistance of novel and improved character in which a positive electrical connection of negligible resistance is established and maintained between the sliding contact and its binding post or terminal, and such connection is maintained insulated from the main shaft without the provision of insulating materials interposed between the metallic conductor and the shaft.

It is a further object of the invention to provide a conductor in the form of a conically wound resilient metallic member having such shape and design that during rotation of one of the fixed points of such member the several turns will be automatically forced away from the center so that both binding of the turns and their accidental contact with the shaft are positively avoided.

The invention also contemplates a novel and improved variable resistance of the rotary type which is simple in character and construction, provides positive and at all times reliable electrical connection of the sliding contact with its fixed terminal and which may be readily manufactured and sold on a practical and commercial scale at a low cost.

Other and further objects and advantages of the invention will become apparent from the following description taken in conjunction with the accompanying drawing; in which

Fig. 1 illustrates a vertical sectional view of a variable resistance embodying the principles of the present invention;

Fig. 2 depicts a top elevational view of the variable resistance shown in Fig. 1;

Fig. 3 is a perspective enlarged view of a conically wound resilient metallic conductor forming part of the variable resistance structure shown in Figs. 1 and 2;

Fig. 4 is a similar view of a modified resilient connecting member; and

Fig. 5 is a vertical sectional view of a modified embodiment of the invention.

Referring now more particularly to Figs. 1 and 2 of the drawing, reference character 10 denotes a base member made of insulating material having an upwardly extending cylindrical wall 11. About this wall is curved a strip of insulating ma-

terial 12 around which are wound closely spaced turns of resistance wire 13 forming the resistance element of the unit. The ends of strip 12 are secured to the cylindrical wall 11 by means of rivets or eyelets 14 also holding conventional terminals in the form of soldering lugs 15 pressed against the terminal portions of the resistance wire thereby establishing electrical contact therewith. The ends of the resistance element strip are similarly held together by means of an eyelet 16 clamping a soldering lug 17.

Base member 10 is provided with a central opening 18 having such dimensions that a shaft 19 may readily pass therethrough. A metal plate 20 is resting against the bottom surface of the base member and has a bearing member 21 rigidly connected to a center opening therein. This bearing member is provided with a shouldered portion 22 upon which the center portions of plate 20 may rest and a threaded sleeve portion 23 adapted to cooperate with a corresponding threaded nut (not shown) for the purpose of one-hole mounting of the complete unit. Bearing member 21 is provided with a longitudinally extending opening 21a of circular cross section forming a sliding fit with shaft 19 in which the shaft may be readily rotated. The shaft is also provided with a circumferential groove 24 at the end of threaded sleeve 23 in which there is inserted a conventional clinch ring 25.

To the upper end of shaft 19 is rigidly connected an insulative disc 26. This rigid connection may be obtained, for example, by tight fit of the shaft into a central opening 27 in the disc and by crimping the weakened upper terminal portions of the shaft upon the disc. This insulative disc 26 has the object of carrying the moving contact structure in the form of a circular plate 29 made of resilient metal from which radially extends a slider or contact arm 30. The major or body portion of circular contact plate 29 is disconnected from the portion bearing the slider by means of a curved incision 31 of the shape illustrated whereby great flexibility of contact arm 30 with respect to plate 29 is obtained and readily yielding resilient pressure of the contact arm upon the resistance element is assured. Against the lower surface of insulative plate 29 is resting flange 32 of a downwardly depending metallic sleeve 33. Contact arm plate 29, insulating plate 26 and metal sleeve 33 are held together by means of a pair of rivets or eyelets 34. It will be noted that both contact arm plate 29 and sleeve 33 end at a distance from shaft 19 sufficient to prevent their direct metallic contact whereby the shaft is insulated from the slider contact under all operating conditions.

Electrical connection between the contact arm and the fixed terminal or soldering lug 17 is provided by means of a relatively thin and resiliently flexible wire 35 wound in the form of a conically-shaped spiral. One end 36 of this wire is extended through eyelet 34 and is soldered to contact plate 29 while its other end 37 is soldered to eyelet 16 holding soldering lug 17.

Spiral 35 is formed with a number of turns sufficient to distribute flexing of the wire during adjustment of the contact arm over a substantial length and thereby to reduce the force required for rotary displacement to a negligible value and also to indefinitely extend the life of the connecting member. The dimensions of the spiral and its winding directions are so correlated to the direction of adjustment of the contact arm that in the initial position the several windings of the spiral

are widely spaced from the center or axial line of the unit so that any additional rotation of the contact arm will tend to unwind the spiral and to force its turns away from shaft 19 and sleeve 33. This form of construction in addition to the conical shape of the spiral, which provides each successive turn with a slightly greater diameter than the preceding one, positively prevents binding of the connecting spiral and thus provides an electrical connection which will function satisfactorily and free from operating difficulties practically indefinitely.

Fig. 3 illustrates an enlarged perspective view of the connecting member wound in a conical spiral form which is preferred for the purposes of the invention. However, equal or similar results may be obtained by providing the connecting member in the form of a flat spiral 40, as this is illustrated in Fig. 4. In this case the turns of the spiral are originally formed in one plane and the ultimate conically-wound spiral structure is automatically obtained when ends 41 and 42 of the spiral are connected to the contact arm and to the corresponding fixed terminal, respectively, whereby the turns of the spiral are slightly pulled apart in the axial direction.

Fig. 5 illustrates a vertical sectional view of a modified embodiment of the present invention. As this embodiment is practically identical with the one described in the foregoing and similar reference characters have been used to denote corresponding parts, its structure and operation will be readily understood without any further description. The difference between the two embodiments resides in the omission of metallic sleeve member 33. Even though in this case there is no mechanical element interposed between the turns of the connecting spiral 35 and the shaft, accidental contact between the spiral member and the shaft is prevented by the shape and the mechanical characteristics of the spiral connecting member, as this has been fully explained in the foregoing. In the absence of sleeve 33, which also has the object of preventing displacements of the shaft in the axial direction, it is desirable to provide a shoulder or small protuberance 43 of appropriate shape in shaft 19 in order to fix shaft 19 in the axial direction.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. A variable resistance comprising in combination a base, an annular resistance element mounted on said base, a shaft rotatably mounted in said base, a metallic contact arm insulatedly secured to said shaft and adapted to make sliding contact with progressive portions of said resistance element during rotary displacement of said shaft, a fixed terminal, and a conically wound spiral spring having its end closest to its axis connected to said contact arm and its end most distant from its axis connected to said terminal, the winding direction of said spiral being so determined with respect to the direction of rotation of said shaft that in the initial position of said shaft the turns of said wire are spaced from said shaft and that during rotation of said shaft said turns will be forced away from said shaft and will positively prevent electrical contact therewith.

2. A variable resistance comprising in combination a base, an annular resistance element

mounted around said base, a shaft rotatably mounted in said base, an insulative member secured to said shaft, a metallic contact arm mounted on said insulative member and insulated from said shaft adapted to make contact with portions of said resistance element during rotary displacement of said shaft, a pair of fixed terminals respectively connected to the ends of said resistance element, a third fixed terminal for said contact arm, and a metallic conductor extending from said contact arm to said third fixed terminal and having the form of a conically wound spiral having its successive turns spaced at increasing distances from the shaft in the initial position of the shaft and being so constructed and arranged that upon rotation of the shaft the spiral will be unwound and its turns will be forced further away from the shaft.

3. A variable resistance comprising in combination a base of insulating material, an annular resistance element mounted on said base, a shaft mounted in said base for rotation within an angle less than 360 degrees, an arm constituted of insulating material secured to said shaft, a resilient contactor extending from said arm into sliding contact-making position with exposed portions of said resistance element, a terminal for said contactor, and an electrical connection between said contactor and said terminal in the form of spring wire wound to a conically tapering spiral, said spiral being wound counter-clockwise from said terminal and having its turns spaced from the shaft whereby said turns will be slightly unwound and forced further away from the shaft during a clockwise rotation of the shaft not exceeding 360 degrees.

4. A variable resistance comprising in combination a base, an annular resistance element mounted on said base, a shaft rotatably mounted in said base, an insulative plate secured to said shaft and rotatable therewith, a resilient contact

- arm extending from said plate and adapted to slidably engage said resistance element, a metallic spacer sleeve depending from said plate and spacedly surrounding the terminal portion of said shaft extending into said base, a fixed terminal, and an electrical conductor in the form of a conically wound spiral spring wire having its ends respectively connected to said contact arm and to said terminal, the winding direction of said spiral wire being so determined with respect to the direction of rotation of said shaft that in the initial position of said shaft the turns of said wire are spaced from said sleeve and that during rotation of said shaft said turns will be forced away from said sleeve.
5. A variable resistance comprising in combination a base, an annular resistance element mounted on said base, a shaft rotatably mounted in said base, a disc constituted of insulating material having its center secured to said shaft, a contact plate on the top surface of said disc and having a radially extending resilient contact arm slidably engageable with said resistance element, a flanged metallic sleeve member depending from the bottom surface of said disc and spacedly surrounding the terminal portions of said shaft, said contact plate and said flanged sleeve being electrically and mechanically connected to each other through said insulative disc, a fixed terminal, and an electrical conductor in the form of a conically wound spiral spring wire having its ends respectively connected to said contact plate and to said terminal, said metallic sleeve acting as a stop member against axial displacements of said shaft, the winding direction of said spiral wire being so determined with respect to the direction of rotation of said shaft that in the initial position of said shaft the turns of said wire are spaced from said sleeve and that during rotation of said shaft said turns will be forced away from said sleeve.
